UNITED STATES PATENT OFFICE.

JOSEPH THOMAS, OF ABERDEEN, WASHINGTON.

VAPOR BATH.

Application filed March 29, 1923. Serial No. 628,585.

To all whom it may concern:

Be it known that I, JOSEPH THOMAS, a citizen of the United States of America, and a resident of Aberdeen, in the county of 5 Grays Harbor and State of Washington, have invented a new and Improved Vapor Bath, of which the following is a description.

My invention relates to vapor baths and 10 particularly to a vapor bath having a rest adapted to be supported in a tub and a canopy adapted to be disposed over the tub in the taking of the vapor bath.

The general object of my present invention is to provide a vapor bath of the indicated class improved in various particulars with respect to the means to support a rest or slab and with respect to the canopy and its supporting means.

20 The nature of the invention and its distinguishing features and advantages will clearly appear as the description proceeds.

Reference is to be had to the accompanying drawings forming a part of this specification, it being understood that the drawings are merely illustrative of one example of the invention.

Figure 1 is a longitudinal vertical section of vapor bath appurtenances embodying my 30 invention showing the same applied in position on a tub;

Figure 2 is a transverse vertical section as indicated by the line 2—2, Figure 1;

Figure 3 is an inverted plan view of the 35 canopy with a portion of the supporting means in horizontal section;

Figure 4 is a detail in section on the line 4—4, Figure 1;

Figure 5 is a fragmentary view showing 40 in elevation a part of the supporting means for the canopy.

In carrying out my invention in accordance with the illustrated example, I provide a series of hangers 10 generally of U-shape 45 and formed with curved ends to hook on edges of a bathtub A at opposite sides. Two of said hangers are shown in the present example and an additional hanger 110 generally of similar form to be hereinafter particularly referred to. The curved ends 11 are covered in practice with a sleeve 12 of rubber, a similar sleeve 112 being provided on the curved ends 111 of the hanger 110. The hangers 10 are adapted when placed on 55 the tub A to support a slab, slats, or the like,

there being a slatted structure 13 having cross cleats 14 thereon, said slats resting on the several hangers to support the one taking the bath suspended in the tub A.

A canopy 15 is provided of suitable fabric 60 and formed with a longitudinal slit 16 through which one's head may protrude.

The canopy 15 is provided with an elastic tape or strip 17 extending about the same at the edge at three sides, that end adjacent the 65 slit 16 having a transverse elastic strip 117 disposed on the canopy inward from the adjacent end edge of said canopy. The elastic edging 17 at the end adjacent the slit 16 has free ends adapted to be tied into a knot as 70 indicated at 217. The elastic edging with cross strip 117 is adapted to be stretched about the tub A beneath the usual edge flange thereof, the cross strip 117 serving to hold that end of the canopy 15 in position 75 even though the knotted ends 217 be united.

The canopy 15 has applied thereto stiffening means adapted to be supported on the tub and additional stiffening and supporting means supported on the hanger 110 as 80 follows: Crossing wires 18 are held to the canopy at the under side by suitable means such as fabric strips 19 encasing said wires except at the lower ends. The lower ends 20 of the wires 18 are directed laterally inward and are curved to effectively rest upon and engage the upper edge of the tub A. The inturned ends 20 are covered by rubber sleeves 21. Extending directly transversely 85 of the canopy 15 and therefore crossing the wires 18 is a bowed spring 22 held in the illustrated example by a casing strip 23 of fabric applied to said canopy. At each lower end of the bowed spring 22 is a reduced and shouldered terminal 26 adapted to 90 engage a keeper 25 stamped up from the terminal portion 24 of the adjacent curved end 111 of the hanger 110.

The canopy 15 is formed with a transverse slit 27 at the foot end of the said 100 canopy and a flap 28 is provided on the canopy and secured thereto at one side of the slit. Said flap may enter through the slit and lie for the major portion at the under side of the canopy for the effective 105 closure of the slit and the flap may be manipulated to permit one's hand to be entered through the canopy from outside for turning the bathtub faucets. Similarly, a slit 29 is formed longitudinally at a side of the 110

canopy 15 through which one of the legs of the person taking the bath may be protruded if desired. A flap 30 arranged similarly to the flap 28 is provided at the slit 29. In 5 the top of the canopy adjacent to the center is a hole 31 normally closed by a flap 32 on the canopy at the under side. Said hole 31 permits of conductor wires being run through the canopy to the interior for various arrangements of lights for heating or 10 for giving color effects in the treatment of a patient.

I prefer in practice to employ additional stiffener bows 33 on the canopy 15 near the 15 ends. Said bows 33 are held by housing strips 34 of fabric sewed or cemented to the underside of the canopy. The lower ends of bows 33 have arched lateral members 35 to rest on the edge of the bathtub (A).

20 I would state in conclusion that while the illustrated example constitutes a practical embodiment of my invention, I do not limit myself strictly to the exact details herein illustrated, since, manifestly, the same can 25 be considerably varied without departure from the spirit of the invention as defined in the appended claims.

Having thus described my invention, I claim:

1. A device for use with vapor baths, 30 comprising approximately U-shaped hangers having out-turned ends adapted to rest on a bathtub at the top, a longitudinally disposed rest supported on said hangers, a canopy adapted to be disposed over the bathtub, means extending about said canopy at the edge to engage the bathtub, stiffener means on the canopy adapted to rest on the bathtub, and additional stiffener means on the canopy adapted to engage one of said 35 hangers.

2. In a device of the class described, a canopy adapted to be positioned over a bathtub, crossed U-shaped stiffener elements on said canopy, certain of said stiffener elements having means at their lower ends to engage the bathtub at opposite side edges, and an additional U-shaped stiffener element crossing the first elements; together with means detachably engageable with said 45 additional stiffener element and adapted to rest on a bathtub.

JOSEPH THOMAS.
